MATERNITY GOWN

Ora L. Hunley, Los Angeles, Calif.

Application July 2, 1934, Serial No. 733,396

3 Claims. (Cl. 2—76)

My invention relates to a maternity gown and has for its principal object, the provision of a relatively simple, practical and inexpensive garment or dress that affords convenience and comfort to the wearer during pregnancy and while the infant is being nursed. A further object of my invention is, to provide a maternity dress or gown wherein a dress of ordinary construction is provided in its front with 10 a vertically disposed opening that extends from the neck of the waist member to a point a substantial distance below the waist line of the dress in order that those portions of the dress that cover the front of the wearer's body may be readily and conveniently adjusted to different sizes and the entire front portion of the dress or gown and the opening therein being covered with a full length apron-like member that is secured to the dress or gown at the shoulders thereof and said apron-like member including a sash located at the waist line in order that it may be secured in proper and convenient position upon the front of the dress or gown.

With the foregoing and other objects in view 25 my invention consists in certain novel features of construction and arrangements of parts that will be hereinafter more fully described and claimed and illustrated in the accompanying drawing in which:

30 Fig. 1 is a front elevational view of a maternity gown constructed in accordance with my invention.

Fig. 2 is a front elevational view of the main body portion of the dress or garment as the same 35 appears before the front apron-like covering member is applied thereto.

Fig. 3 is a front elevational view of the apron-like member that covers the entire front of the dress or gown.

40 Fig. 4 is a horizontal section taken on the line 4—4 of Fig. 1.

Referring by numerals to the accompanying drawing which illustrates a preferred embodiment of my invention, 10 designates the waist of the gown or dress which may be formed of any suitable material and cut to any desired pattern and said waist may or may not be provided with sleeves such as 11.

Suitably secured to the lower edge of the waist member 10, is a skirt 12 and the line 13 on which the waist and skirt are secured forms the waist line of the gown.

Extending from the neck opening 14 of the waist member downwardly to a substantial distance below the waist line, is a vertically disposed

opening 15, preferably of uniform width throughout its length.

Suitable ties such as 16 are secured at one end to the waist line of the gown, preferably at points immediately adjacent the edge of the vertical opening 15 and if desired similar ties 17 may be secured at one end to the material forming the waist or skirt at points above or below the waist line. These ties 16 and 17 provide means for connecting those portions of the garment to the sides 10 of opening 15 that extends vertically on the front of the wearer's body.

The front covering member 18 of the gown is in the form of a full length apron and formed in the upper central portion thereof is a neck opening 19 that may be trimmed as desired. The upper edges of the front member 18 to the sides of the neck opening overlie the shoulder portions of the waist member 10 of the gown and said upper edges are suitably secured to the shoulder portions of the gown, preferably along the shoulder seams by rows of stitching 20.

The upper portions of the side edges of member 18 coincide with the arm openings in the waist 10 and said edges are suitably secured to said waist member 10 along the front portions of the arm openings therein, preferably by rows of stitching such as 21.

Thus when the front member 18 is applied to the gown as illustrated in Fig. 1 it covers the entire front portion of said gown and the width of the front member is such that its side edges extend slightly beyond or rearwardly from the vertical side seams of the waist 10 and skirt 12 of the garment.

Extending across the front face of front member 18 at or near the waist line thereof, in a sash 22 that is suitably secured, preferably by means of stitches to the side edges of said front member and the end portions of this sash are of such length as to pass around the back of the wearer's body and be tied together, thereby holding the front covering member in proper position upon the front portion of the gown.

The opening 15 provides simple and convenient means whereby the front portion of the gown may be conveniently adjusted on the front portion of the wearer's body and after such adjustment the side edges of the front opening may be connected by ties 15 and 17.

The front member 18 provides an effective closure for the opening 15 and the ends of the sash 22 may be adjustably connected at the convenience of the wearer.

The opening 15 in the gown provides for the 55

convenient carrying out of the nursing functions and during such procedure the front member 18 may be readily turned from one side to the other.

An especially desirable feature of my invention 5 is, the provision of the front apron-like member which is attached only to the upper or shoulder portions of the waist member 10 so that the weight of the front member is suspended entirely from the shoulders and as said front member covers the entire front portion of the garment comprising the waist 10 and skirt 12 and the opening 15 therein, it imparts to the gown a neat and finished appearance.

Further, the provision of the opening 15 in the 10 body covering member of the garment, prevents the front portion of the skirt thereof from raising or becoming elevated as the upper portion of the gown is adjusted to different sizes of the body and thus an even hem line at the lower end of 15 the garment is preserved.

The garment with the ends of the ties 16 and 20 17 and the ends of sash 22 disengaged from each other, is put on over the head of the wearer and after being put on, the ends of the ties 16 are 25 connected across the lower portion of the opening 15 and the ends of sash 22 are tied together on the back of the garment.

The neck opening 14 in the waist member 10 and the neck opening 19 formed in the upper 30 portion of front member 18 may be readily spread open when the upper portion of the garment passes over the head of the wearer.

It will be noted that my improved maternity 35 gown is entirely devoid of buttons and button holes, hooks and eyes, snap fasteners and the like and that ties are used in the place thereof. As a result the gown may be very easily and quickly adjusted to the convenience and with very little effort on the part of the wearer.

Thus it will be seen that I have provided a 40 maternity gown that is relatively simple in construction, inexpensive of manufacture and very effective in performing the functions for which it is intended.

It will be understood that minor changes in the size, form and construction of the various parts of my improved maternity gown may be made and substituted for those herein shown and described without departing from the spirit of the invention, 5 the scope of which is set forth in the appended claims.

I claim as my invention:

1. In a maternity gown, a body covering member, comprising a waist and skirt, there being a 10 vertically disposed opening of substantial width extending downward from the neck opening of the waist to a substantial distance below the waist line of the garment, ties each secured at one end to the edges of the garment at the sides of the 15 opening therein and a front apron-like member secured to the upper portion of the waist of the body covering member and entirely covering the opening therein.

2. In a maternity gown, a body covering garment, comprising a waist and skirt, there being an opening of substantial width formed in the front of said garment and extending from the neck opening thereof downwardly to a point a 20 substantial distance below the point of connection 25 between the waist and skirt and a front apron-like member secured to the upper portion of said body covering garment for entirely covering the front portion thereof and the opening therein.

3. In a maternity gown, a body covering garment, comprising a waist and skirt, there being an opening of substantial width formed in the front of said garment and extending from the neck opening thereof downwardly to a point a 30 substantial distance below the point of connection 35 between the waist and skirt, a front apron-like member secured to the upper portion of said body covering garment for entirely covering the front portion of said body covering garment and the opening therein and ties connected at one end 40 to the side edges of said front covering member.

ORA L. HUNLEY.
